UNITED STATES PATENT OFFICE.

JAMES McCREADIE ROBERTSON, OF DUBLIN, IRELAND.

MACHINE FOR COMPRESSING AND BINDING OR CORDING TOBACCO.

SPECIFICATION forming part of Letters Patent No. 551,838, dated December 24, 1895.

Application filed January 19, 1895. Serial No. 535,455. (No model.) Patented in England March 9, 1894, No. 4,935; in France January 16, 1895, No. 244,390, and in Belgium January 18, 1895, No. 113,686.

To all whom it may concern.

Be it known that I, JAMES McCREADIE ROBERTSON, a subject of the Queen of Great Britain and Ireland, residing at Dublin, Ireland, 5 have invented certain Improvements in Machines for Compressing and Binding or Cording Tobacco, (for which patents have been obtained in Great Britain March 9, 1894, No. 4,935; in France January 16, 1895, No. 244,390; 10 in Belgium January 18, 1895, No. 113,686, and application filed in Germany January 4, 1895, not yet granted and not numbered;) and I do hereby declare that the following is a full, 15 clear, and exact description of the invention, which will enable others skilled in the art to which it appertains to make and use the same.

This invention has for its object improvements in machinery whereby the process of compressing and binding or cording plug-to- 20 bacco may be accomplished in a simpler and more efficient and economical manner than heretofore.

In order that my said invention may be readily understood and carried into practice, 25 I will proceed to describe it in connection with the accompanying drawings.

Figure 1 is a plan, and Fig. 2 a side elevation, of my improved machinery. Fig. 3 is an end view of certain parts partly in section. 30 Fig. 4 is a side view of the same parts partly in section. Fig. 5 is an end view of certain parts. Fig. 6 is a side view of the same, and Fig. 7 is a vertical section of a portion.

The drawings show the plug of tobacco as 35 having been partly acted upon.

Similar letters and numerals of reference indicate corresponding parts in all the figures where they appear.

A indicates the frame of the machine; B 40 and B', the heads which constitute the bearings for the tobacco-carrying spindles or bearers C and C', each capable of yielding end- wise to a small extent, and the pulleys 1, 2, and 3, the head B being fixed, while B' is capable of being shifted for the purpose of accom- 45 modating the length of tobacco to be cored. The pulleys 1 and 3 are loose to take an open and a crossed belt from a driving pulley, (not shown,) whereby the rotation of

pulley 2, which is fast on the arbor, may be 50 reversed by the shifting of the respective belts by guide-forks 4 and 5 carried on shifting- rods 6 and 7 mounted on each side of the machine.

8 is a longitudinal screw-spindle carried in 55 suitable bearings and operated by the pulley 2 through spur-gears 9 and 10. Over this screw-spindle is mounted a carriage-saddle 11, Figs. 3 and 4, which can be traversed longitudinally and affords a long and efficient 60 bearing for the revolving head 12, the latter in turn supporting the overhung deep-flanged loose pulley or bobbin 13, on which a just sufficient quantity of the binding-cord 37 is coiled. 65

On the face of the revolving head 12 is pivoted a guide-pawl 14, grooved on its upper and outer edge to facilitate the passage of the binding-cord 37 in transit from the loose pulley 13 through the aperture 15 to be wound 70 tightly upon the tobacco-plug 16, as herein- after described.

The loose pulley or bobbin 13 is provided with an ordinary brake-band 17 for the purpose of regulating the tension of the cord 37 75 in the process of binding. This brake may be actuated by a spring with provisions for adjusting, as practiced in kindred arts.

In front of the revolving head and on the same carriage-saddle 11 is erected an eye or 80 guide D, Figs. 5 and 6, consisting of two pieces 18 and 19, hinged at 20 and secured by a clamping device at 21. This does not revolve, but simply traverses longitudinally with the traversing of the head. At opposite 85 extremities of the diameter of the eye and at right angles to its plane are mounted rollers 22, whose peripheries are shaped to suit the section of the circle which they occupy. The vertical rods on which these rollers are carried are provided with spiral springs (not shown) operated by the thumb-screws 25, whereby the pressure of the rollers upon the cored plug may be regulated at pleasure. 90

From the carriage-saddle the bobbin 26 is 95 suspended which carries the binding-cord 37, and from which the latter is transferred to the loose pulley 13 as required.

The pinion 29 is smoothly bored to fit on the exterior of the screw-threads of the screw-spindle 8 and coupled therewith, so as to be revolved thereby by means of a feather 24, 5 engaging the spline shown therein and in the screw, whereby a rotary motion is imparted to the pinion, which in turn is communicated through the pinions 28 and 27 to the revolving head 12, (the pinion 27 being fast on same,) 10 while meantime the carriage-saddle 11 is moved longitudinally by the bracket 30, which is threaded to engage the screw 8. Thus as the screw-spindle revolves a compound motion—rotary and horizontal—is communicated to the revolving head 12. This motion may be reversed at pleasure by the reversion of the motion of the screw-spindle. 15

32 is a stop fixed adjustably on the rod 6 and capable of being partially revolved. It 20 has a long and a short arm and a handle, by which it may be turned to present either to be struck by the saddle 11 in its return motion. Both arms of the stop 32, and also the single stop 31 which arrests the motion in the other 25 direction, are elastic.

The action of my improved machinery is as follows: The carriage-saddle 11 having been brought to its starting position near the fixed head B, the plug of tobacco to be compressed 30 and bound is inserted through the revolving head 12 and guide-eye or stay D, and is secured at both ends by pressure against (or by penetrating suitable sockets in) the free ends of spindles C and C'. In this position the 35 plug is held stationary during the process of binding. The free end of the binding-cord (of which a sufficient quantity for binding one plug is carried on the loose pulley 13) extends through aperture 15 and along the edge 40 of pawl 14, and is by the fingers of the attendant or by any suitable device pressed against and caused to adhere to the tobacco. The machine is then started by the open belt on fast pulley 2, whereupon the screw-spindle 45 8 carries forward the carriage-saddle 11 through the agency of bracket 30 and communicates rotary motion by the pinions 27, 28 and 29 to the revolving head 12, which in its revolutions around the plug 16, as indicated by the arrow, Fig. 3, pays out the binding-cord 37 from the loose pulley 13, winding 50 the same in regular convolutions until the tobacco is completely covered. On arriving at the end of its travel the carriage strikes 55 an arm 31, attached to rod 7, whereby the belt is shifted from fast pulley 2 onto the loose pulley 3 and the machine stops when the corded plug is removed. The cross-belt is now shifted to fast pulley 2, whereupon the 60 rotation of the screw-spindle is reversed and the carriage-saddle 11 returns to its original position. When it has completed a certain portion of the return journey it strikes the long arm of the pivoted stop 32, attached to

the longitudinal sliding rod 6, and moves it 65 so as to shift the cross-belt upon the loose pulley 1, and the machine stops. Then the end of a fresh supply of the cord 37 from the large spool 26 is attached to the bobbin 13, the stop 32 is partially revolved so as to raise 70 its long arm out of use and present its short arm in the longitudinal portion ready to serve, and a pin 33 is moved longitudinally through the revolving head 12 into a corresponding aperture in the bobbin 13, whereby the latter 75 is temporarily keyed to the former. Next, the rod 6 being again shifted to replace the belt upon the fast pulley 2 and continue the motion, the bobbin 13 turns with the revolving head during the remainder of the return 80 journey and automatically draws off from the supply-bobbin 26 and stores upon itself a sufficient length of cord 37 for the next operation. At the end of the return movement the carriage-saddle 11 strikes the shorter arm of 85 the revolving stop 32 and again moves the rod 6, and the machine is again stopped. Then the pin 33 is again withdrawn and the cord 37 is cut and the end of the portion stored on the bobbin 13 is rove through the hole 15 and connected to the next plug of tobacco, and the 90 covering proceeds as before. During the act of binding there is a natural tendency on the part of the plug to elongate or expand, and to provide for this tendency the spindles C and C' 95 impinge against spiral springs 34 and 35, Fig. 1, which yield as the plug elongates or expands, and thus buckling is avoided.

It is obvious that plugs of varying thicknesses and lengths may be readily corded by 100 the machinery herein described, making the necessary changes in the adjustment of the machine.

To counteract the pressure of the plug caused by the pull of the cord 37 in the act 105 of binding the tobacco, a roller 36 is fixed on the face of the revolving head.

Having now described the nature of my invention, what I claim is—

1. In apparatus for compressing and cord- 110 ing tobacco, the improved binding mechanism comprising a carriage saddle 11, arranged to move longitudinally, in combination with a revolving head 12, and loose pulley or bobbin 13, the revolving head having a guide 15 for 115 the binding, and also with the supports C C', adapted to hold the plug stationary, all arranged and operating in the manner substantially as herein specified.

2. In apparatus for compressing and cord- 120 ing tobacco, binding mechanism comprising a carriage saddle 11, a revolving head 12 and loose pulley or bobbin 13, the revolving head being provided with an aperture 15, in combination with suitable means for supporting 125 the plug, and with the guide pawl 14, and guide D, constructed, arranged and operating in the manner substantially as described.

3. In apparatus for compressing and cord-
ing tobacco, the mechanism described, con-
sisting of the bearers C, C', carriage saddle
11, revolving head 12 and bobbin 13, the guide
5 D in line therewith, the bracket 30, splined
screw spindle 8, splined spur gear 29, and the
connecting gears 27 and 28, all arranged for joint operation substantially as herein speci-
fied.

Dated the 6th day of December, 1894.

JAMES McCREADIE ROBERTSON.
